(57) **CLAIM**

The ornamental design for a portable audio speaker system, as shown and described.

DESCRIPTION

FIG. 1 is a front, right side perspective view of a portable audio speaker system, embodying our new design;
FIG. 2 is a front elevation view thereof;
FIG. 3 is a left side elevation view thereof, showing a (covered) audio ingress and Universal Serial Bus (“USB”) ports;
FIG. 4 is a right side elevation view thereof;
FIG. 5 is a top plan view thereof, showing a number of control buttons and an alphanumeric display; and,
FIG. 6 is a bottom plan view thereof.
